PLC.(57) **CLAIM**

The ornamental design for punch press, as shown and described.

DESCRIPTION

FIG. 1 is a perspective view of an embodiment of a portion of a punch press, showing my new design;

FIG. 2 is a front elevational view of the embodiment of FIG. 1;

FIG. 3 is a rear elevational view of the embodiment of FIG. 1;

FIG. 4 is a right side elevational view of the embodiment of FIG. 1;

FIG. 5 is a left side elevational view of the embodiment of FIG. 1; and,

FIG. 6 is a top plan view of the embodiment of FIG. 1.

The broken lines are for illustrative purposes only and form no part of the claimed design. The lines consisting of long lines and dots indicate border lines only between the claimed portion and unclaimed portion of the design. Shading is added only for expressing surface contour of the design.
